UNITED STATES PATENT OFFICE.

HENRY HELLMAN AND LEWIS CONDICT BAYLES, OF JOHANNESBURG, TRANSVAAL.

ROCK-DRILLING MACHINE OR ENGINE.

No. 872,417.

Specification of Letters Patent.

Patented Dec. 3, 1907.

Application filed July 12, 1905. Serial No. 289,405.

To all whom it may concern:

Be it known that we, HENRY HELLMAN and LEWIS CONDICT BAYLES, citizens of the United States, both residing at Johannesburg, Transvaal, have invented certain new and useful Improvements in Rock-Drilling Machines or Engines, of which the following is a specification.

Our invention has reference to drilling machines or engines, and in particular to that class of engine adapted to be actuated by compressed air or other elastic or expansive gaseous fluid.

The invention has for its especial object the providing novel and simple means for producing and transmitting to the drill bit or boring tool an intermittent rotary motion.

The invention will now be described in detail by aid of the accompanying drawings, 20 wherein

Figure 1 is a longitudinal elevation of the machine showing the external and supporting casing partly in section. Fig. 2 is a longitudinal section drawn to an enlarged scale, 25 the plane of section being represented by the dotted lines Figs. 8, 9 and 10. Fig. 3 is a transverse section of Fig. 2 on line $x-x$. Fig. 4 is a transverse section of Fig. 2 on line $y-y$. Fig. 5 is a transverse section of Fig. 2 30 on line $z-z$. Fig. 6 is a transverse section of Fig. 2 on line $x-y$. Fig. 7 is a transverse section of Fig. 2 on line $x-z$. Fig. 8 is a transverse section of Fig. 2 on line $y-z$. Fig. 9 is a transverse section of Fig. 2 on line 35 x^1-x^1 . Fig. 10 is a transverse section of Fig. 2 on line y^1-y^1 . Fig. 11 is a transverse section of Fig. 2 on line z^1-z^1 . Fig. 12 is a transverse section of Fig. 2 on x^1-y^1 . Fig. 40 13 is a transverse section of Fig. 2 on line x^1-z^1 . Fig. 14 is a transverse section of Fig. 2 on line y^1-z^1 . Fig. 15 is a longitudinal section of the front head and a portion of the front end of the power cylinder showing a slightly modified construction. Fig. 45 16 is a transverse section of a portion of the external casing and the adjustable supporting sleeve, illustrating a modified means for securing the latter round the casing, and Fig. 17 is a sectional elevation of the front 50 end of the machine showing the power piston and impact piece in their inoperative positions, when the machine is used as a non-percussive machine.

In the drawings 1 is a hollow cylinder 55 which constitutes a protective casing in

which the machine proper is slidingly mounted or adapted to be moved longitudinally thereof in either direction.

2 represents a sleeve or band which encircles the protective casing 1 and serves for 60 adjustably attaching the same to a column clamp or other supporting device. The construction of this sleeve 2 is fully illustrated in Figs. 1 and 9. As shown it consists of the split band or sleeve constructed with the 65 cone 3, by which it can be firmly secured in a column clamp. Instead of the cone 3 it may be otherwise constructed to allow of its being attached either to a column clamp or any other suitable support. 70

One end of the sleeve 2 is bifurcated or constructed with the two parts 4, separated by a space 5, and the other end 6 is shaped to project into or fit the bifurcation. The ends of the parts 4 and the end of the part 6 are 75 turned upwards and inwards in the form of hooks 7 (see Fig. 9). When the band 2 is encircling the casing 1 and the part 6 is in the bifurcation a space 8 is left between the upturned or hooked parts 7, in which space 80 8 is placed a taper key 9. When the key is driven in one direction it forces the part 6 forward into the bifurcation, reduces the internal diameter of the sleeve and so tightens it round the casing 1. When the key is 85 driven in the reverse direction, the band 2 releases its grip of the casing 1 and allows the casing to be adjusted therein or moved longitudinally thereof in either direction. In the modification of this arrangement as illus 90 trated in Fig. 16, the ends of the sleeve 2 are constructed with the projections 7^a forming the recesses 8^a. Over the projections 7^a is arranged a tapered key 9^a which is shaped to fit the recesses 8^a. This key 9^a when driven 95 in one direction draws the projections 7^a together and so tightens the sleeve 2 on the casing 1.

The power cylinder represented at 11 is arranged concentrically inside the protective casing 1 and adapted to slide longitudinally thereof in either direction within certain limits. In the forward end of the casing 1 and encircling the power cylinder 11 is a bushing 12 shown secured to the end 100 of the casing 1 by means of rivets 13. The internal diameter of this bushing 12 is such that it makes a good sliding fit with the power cylinder 11. In the bushing 12 and 105 formed parallel with the longitudinal axis of 110

the casing 1 or at any suitable angle or inclination thereto, are holes or ports 14 (see Figs. 2 and 10) which communicate with the interior of the casing 1 and serve for directing the whole or a portion of the exhaust actuating fluid from said casing 1 towards the face upon which the machine is operating to prevent any of the cuttings emanating from the bore hole being thrown in the direction 10 of the machine. Exhaust ports 15 are shown formed in the forward end of the casing 1, which may be used either alone or in conjunction with the ports 14 in the bushing 12, or if preferred, be dispensed with 15 when the latter are employed.

The power cylinder 11 at its forward end is shown constructed with an external screw-thread 16 round a reduced portion 17. Over this portion 17 is screwed the front head 20 18. The front head 18 is constructed with a hole 19 of square, or other polygonal cross section, and at the rear of the hole 19 with a cylindrical cavity 20. In the forward end of the power cylinder 11 is located an impact piece 21 which serves to receive the impacts of the power piston 22 or reciprocating percussive member and to transmit the same to the drill bit or boring tool 23. The impact piece 21 in its rear portion is made a sliding fit in the bore of the power cylinder 11, and in its front portion is made somewhat larger and a sliding fit in the cylindrical cavity 20 in the inner end of the front head 18. The cavity 20 in the front head 18 being of greater 35 diameter than the bore of the cylinder 11 forms an abutment or shoulder 24 for the enlarged front portion of the impact piece 21. The shank end of the drill steel or bit 23 is made of the same shape in transverse 40 section as the transverse section of the hole 19 in the front head and so that it may slide longitudinally thereof, but is compelled to rotate with it. A hole 25 is formed longitudinally of the drill steel 23 along which 45 water is conducted to the cutting extremity of said bit, which converts the comminuted rock or cuttings into sludge and prevents it emanating from the bore-hole in the form of dust.

50 A small hole 26 is formed longitudinally of the impact piece 21 through which a quantity of the actuating fluid may pass from the front end of the power cylinder 11 to assist in forcing the water through the steel 23 and 55 ejecting the cuttings from the bottom of the hole being drilled. In the front end of the impact piece 21 is formed a hole 27 somewhat larger in diameter than the hole 26 which leads into or communicates with it 60 at the bottom.

Round the enlarged part of the impact piece 21 is formed an annular groove 28, and from the annular groove 28 ports or passages 29 are formed communicating with the hole 65 27 at or near the bottom or at the point

where the hole 26 opens into it. These ports or passages 29 are as shown preferably angularly disposed in relation to the longitudinal axis of the impact piece 21 and inclined in a forward direction from the annular groove 28 to the hole 27. The ports 29 serve as the water ducts along which the water passes from the annular groove 28 to the hole 27 and from the latter along the coincident hole 25 in the drill steel 23. 70 The actuating gaseous fluid passing along the hole 26 as it enters the hole 27 expands, and by tending to create a vacuum in the water ducts 29 draws the water by suction and conveys it along the hole 25 in the drill 75 steel 23 to the cutting extremity thereof. 80

Round the front head 18 is arranged a swivel ring 30. This swivel ring 30 on the one side rests against a shoulder 31 formed by an abutment on the front head 18 and on the other side is held in position by means of a nut 32 and locknut 33 screwed over the front head 18. The swivel ring 30 is constructed with an internal annular groove or recess 34 and through the front head 18 are formed holes 35 which place said annular groove 34 in communication with the annular groove 28 in the impact piece 21. As the impact piece 21 has a limited movement inside the front head 18 (when it pushes the 95 drill steel 23 forward) the annular groove 28 is made sufficiently wide to remain in communication with the ports 35 in the front head 18 at any position said impact piece 21 may assume in the front head 18. 100

In a hole 36 in the swivel ring 30 which communicates with the annular groove 34 is arranged a hose stem 37 formed with a head or enlargement 38 at the inner end. The stem 37 is revolvably attached to the 105 swivel ring 30 by means of the screw plug 39. To the outer extremity of the stem 37 is attached the hosepipe 40 by means of the hose-clamp 41. This construction provides a convenient detachable connection between 110 the hose 40 and swivel 30 and obviates the defects of the previous constructions of such devices. The hose pipe 40 may lead to any source of water supply from which the water will be drawn by suction or forced 115 by pressure into the swivel ring 30 and from the latter through the impact piece 21 to the drill steel 23.

In the modified construction illustrated in longitudinal section in Fig. 15, the impact 120 piece 21 as a separate part is dispensed with, and the shank of the drill 23^a is constructed in one piece with the cylindrical extension 21^a of reduced diameter which projects in a rearward direction through the front head 125 18^a into the forward end of the bore of the cylinder 11. The hole 25^a along which the water is conducted to the cutting end of the drill steel 23^a is carried through to the inner 130 end of the shank so that a quantity of the

actuating fluid may pass along it out of the cylinder 11. The annular recess 28^a is formed in the front head 18^a and the angular and forwardly inclined ports 29^a between said recess 28^a and the longitudinal hole 25^a are formed in the cylindrical extension 21^a of the shank. The part 23^a of the shank is made of any suitable polygonal transverse section to fit the polygonal hole 19^a in the front head 18^a. The swivel 30^a constructed with the internal annular groove 34^a is arranged round the front head in a similar manner to that described with reference to Fig. 2, and is secured thereon by means of 15 the nut 32^a and lock-nut 33^a in precisely the same manner. The holes 35^a are formed radially or otherwise in the front head to place the annular recess 28^a in communication with the annular groove 34^a in the 20 swivel piece 30^a. The swivel piece 30^a is constructed with the tapped hole 36^a for the hose connection. The front head 18^a is shown screwed over the front end of the power cylinder 11 as indicated at 16^a to 25 securely attach it thereto.

An exhaust port 42 is formed in the front end of the power cylinder 11 which in the normal running of the machine is closed by the impact piece 21, or (as in the arrangement shown in Fig. 15) by the inner end of the shank of the drill. In the event of the impact piece 21 being driven forward beyond the exhaust port 42 and the piston 22 overlapping the supply port 43 then any actuating fluid which may leak past the piston 22 will escape through said exhaust port 42, and prevent the reversal of the piston 22 until the impact piece 21 is moved back to close said exhaust port 42.

Attached to the rear end of the power cylinder 11 is the valve 44 which controls the admission of the actuating fluid alternately to either end of the power piston 22. Longitudinally of the cylinder 11 is formed a port 43 which constitutes the main supply port for the forward end of the power cylinder 11 and communicates with the latter at the rear of the impact piece 21. 45 is the exhaust port for the power cylinder exhausting into the protecting casing 1.

The rear end of the power cylinder 11 is formed with an external screw thread 46. Next the end of the cylinder 11 is placed a valve plate 47 which is formed with a hole 48 communicating with the main supply port 43 for the forward end of the cylinder 11 and with a central hole 49 through which the actuating fluid passes from the valve 44 to the rear end of the power cylinder 11. 60 50 is the valve box in which is arranged the valve 44. The valve 44, valve box 50 and the valve plate 47, are retained in position by means of the hollow cylindrical piece 51, which constitutes the valve box cap which 65 is screwed over the rear end of the power

cylinder 11. As shown, the valve 44 (which in itself does not constitute any feature of the present invention) is a well known form of valve for this class of machine and the manner in which it operates to alternately admit 70 the actuating fluid to either end of the power cylinder 11 will be well understood. Instead of employing a valve of the construction shown in the drawing, it will be obvious that any other form of valve may be used 75 which is adapted to automatically control the admission of the actuating fluid to either end of the power cylinder 11.

In the valve box cap 51 and round that portion which incloses the valve box 50 are 80 formed a number of ports 52 which serve as the exhaust ports from the valve 44 and communicate with or open into the protective casing 1. In the circumference of the valve box cap 51 is constructed an annular 85 groove in which are located a packing ring 53 and a packing ring spring 54, which serves to keep said packing tightly pressed against the internal walls of the outer-casing 1 and so prevents the passage of the actuating 90 fluid admitted to the casing 1 at the rear of said packing 53 passing to the front portion of the casing or beyond said packing. 55 is a port which constitutes the inlet for the gaseous fluid to the valve 44. This port 55 95 communicates with the interior of the valve box cap 51 at the back of the valve box 50 and the actuating fluid enters the valve box 50 through the supply ports 56, 57. 58 is a port communicating with the port 43 for 100 the forward end of the cylinder.

In the center of the valve box cap 51 is a screw threaded hole in which is screwed a cylindrical piece 59 which constitutes the ratchet box. This piece 59 is made hollow 105 at its rear end and on the inner surface is constructed with ratchet teeth 60 as seen in Fig. 7. Between the ratchet box 59 and the end of the valve box cap 51 are interposed a number of rings or liners 61, which 110 serve for taking up any play resulting from wear between the rotating surfaces, the valve box cap 51 and ratchet box 59 being free to rotate relative to a hollow cylindrical piece 62 and the tail pipe 63 to which it is 115 attached. The hollow cylindrical piece 62 surrounding the ratchet box 59 is at its forward end constructed with a flange 64 which fits into a recess formed between the valve box cap 51 and ratchet box 59. In an annular recess formed round the cylindrical piece 62 and valve box cap 51 and inclosing the joint between them, is a leather or other suitable ring 65, and 66 is a spring arranged round the leather ring 65. 120

Screwed into the rear end of the cylindrical piece 62, is a tail pipe 63, which extends for some distance in a rearward direction through the rear end of the protective casing 1. This tail pipe 63 is as shown made 130

of polygonal external section, or constructed with a number of flat faces which serve for preventing its rotation. Surrounding the tail pipe 63 and screwed over the rear end 5 of the protective casing 1 is the casing cap 67 which internally is made of the same shape as the external shape of the tail pipe 63, or otherwise constructed to prevent said tail pipe 63 rotating therein. Round the tail pipe 63 at the rear end of the casing cap 10 67 is placed a cup leather packing 68 and gland 69, secured by the gland nut 70 screwed over the end of the casing cap 67.

The bore or interior walls of the tail pipe 15 63 are made parallel for a portion of their length, say to the point *a*, then tapered inwards for a portion of their length or to the point *b* and then made parallel to the end, where it abuts the rear end of the ratchet 20 box 59.

Inside the tail pipe 63 is arranged a cylinder 71 which is tapered for the greater portion of its length to correspond to the tapered portion of the bore of the tail pipe 63. This 25 cylinder 71 is made a tight fit with the interior of the tail pipe 63.

In the cylinder 71 is located a piston 72 which is constructed with a rearward extension or tail piece 73. This tail piece 73 projects into a hole 74 in the rear end of the cylinder 71 and when the piston 72 is reciprocated inside the cylinder 71 it moves backwards and forwards therein. Inside the cylinder 71 and round the inner end of the hole 30 74 is screwed a nut 75 (see Fig. 5) which is shaped internally to correspond to the shape of the tail piece 73 and serves for preventing the rotation of the piston 72 inside the cylinder 71. The piston 72 is constructed with a 35 longitudinal hole 76, in front of which is fitted a rifle nut 77, through which works a rifle bar 78. The rifle bar 78 at its forward extremity is constructed with a head 79 which is located in the ratchet box 59. In circular 40 recesses 81 formed in this head 79 are fitted the ratchets or pawls 82 which are maintained in engagement with the ratchet teeth 60 in the ratchet box 59 through the medium of pins 83 and springs 84 located in holes 45 80 formed in the head 79. A steady pin 85 is fitted in holes formed in the front end of the head 79 and rear end of the ratchet box 59 on the inside to maintain true axial alignment of these parts. Between the rear end 50 of the head 79 of the rifle bar 78 and the forward end of the cylinder 71 is located a rotation washer or plate 86 which serves to keep the pawls 82 in position in the head 79 and in engagement with the ratchet teeth 60, and 55 60 also acts as a bearing for the forward end of the rifle bar 78. The hole 76 in the piston 72 into which the rifle bar 78 projects is made sufficiently deep to allow for the full stroke of the piston 72, and the parts are so arranged that when the piston 72 is at the end 65

of its rearward stroke, a portion of the rifle bar 78 still remains in the rifle nut 77 so that it is not disengaged thereby.

In the cylinder 71 (see Figs. 2, 5, and 6) is formed a port 87 along which the actuating fluid is conducted to and exhausted from the forward end of the piston 72. 88, 89 represent the main supply ports and 90, 91, the exhaust ports. 92 is a small port from the interior of the cylinder 71 to the valve 93 by 75 means of which air is conducted for reversing the position of the valve 93. The actuating fluid is admitted to the protective casing 1 through an inlet 94 in the casing cap 67. This inlet 94 is fitted with a bush 95 formed 80 with an internal screw thread adapted to receive the throttle valve on the actuating fluid supply pipe. To the inner end of this bush 95 is fixed a gauze wire strainer 96 which serves for preventing the ingress into the 85 machine of any particles of solid matter or other impurities that may be contained in or carried by the actuating fluid. This strainer 96 being fixed to the inner end of the bush 95 provides a ready means for removing it when 90 required to cleanse it or for any other purpose. The actuating fluid passes from the inlet 94 along the groove 97 into the rear end of the protective casing 1. In the forward end of the tail pipe 63 is formed a port 98 95 which communicates with the port 89. A similar port (not shown) is formed in the tail pipe 63 communicating with the port 88.

On the rear end of the cylinder 71 is fixed a valve plate 99 and next the valve plate 99 a 100 valve box 100 in which is located the valve 93, all of which are of the ordinary construction as previously referred to in connection with the valve 44 for the power cylinder 11.

The valve 93 is adapted to automatically 105 admit the actuating fluid to the hole 101 (which constitutes the supply port to the rear end of the piston 72) and the port 87 communicating with the forward end of said piston 72, said valve 93 also serving alternately to place the opposite ends of the cylinder 71 in communication with the exhaust ports 90, 91. The port 98 into which the actuating gaseous fluid passes from the protective casing 1 communicates with the 115 valve box 100 by the port 89, as seen in Fig. 2. At the rear of the valve box 100 is placed a circular plate 102 which in the outside is formed with a recess 103. In the rear end of the tail pipe 63 is located a cross head 104 120 which is fixed by means of the bolts 105. These bolts 105 also serve to secure the handle 106 to the rear end of the protective casing 1. At the center of the crosshead 104 is arranged a bolt 107 fitted with a locknut 108 125 which at its inner end projects into the recess 103 in the circular plate 102 and serves to secure in position the parts at the rear end of the cylinder 71. The handle 106 is provided for the purpose of retracting or sliding 130

the machine in a rearward direction inside the protective casing 1.

On the casing cap 67 is fitted an oiler or device 109 for introducing a lubricant between said cap 67 and the tail pipe 63.

The manner in which the machine operates is as follows:—The actuating fluid entering at the inlet 94 after passing through the strainer 96, passes along the port 97 in the casing cap 67 into the rear end of the protective casing 1. From the casing 1 it passes through the port 55 into the rear end of the valve box cap 51, and the valve 44 is therewith automatically actuated to alternately admit the fluid to either end of the power cylinder 11 or either side of the power piston 22 and to place the same in communication with exhaust through the ports 45, 52, protective casing 1 and ports 14, 15 in the bushing 12 and forward end of the protective casing 1. The actuating fluid being unable to pass the packing ring 53 exerts its expansive force on the rear end of the valve box cap 51, keeps the power cylinder 11 pressed forward and the rock-drill or bit 23 up to its work or in contact with the surface of the rock being operated upon. By this means the drill 23 is automatically fed forward as the hole deepens. The actuating fluid being used at its initial pressure for the purpose of feeding the drill, it is only requisite to provide a comparatively small area upon which the fluid can act to accomplish this. The attachment to the rear end of the valve box cap 51 or power cylinder 11 inside the protective casing 1, of the cylinder 71, by reducing the area upon which the fluid can exert its pressure, permits of its being utilized as the means for feeding the drill. At the same time the actuating fluid passes from the external casing 1 through port 98 into the port 89 and along the latter to the valve box 100, and by means of the valve 93 is automatically admitted alternately through the opening 101 and port 87 to the rear and front end of the piston 72. In Fig. 2 the valve 93 is shown placing the rear end of the piston 72 in communication with the port 89 to admit the actuating fluid, and with the port 87 communicating with the front end of said piston 72, open to exhaust. The actuating fluid forces the piston 72 in a forward direction and the latter being restricted to a rectilinear non-rotative motion inside its cylinder 71, the nut 77 rotates the rifle bar 78 and with it the head 79. The ratchet box 59 being rigidly attached to the valve box cap 51 and through the latter to the power cylinder 11 imparts a corresponding intermittent rotary motion to said power cylinder 11 and through the latter to the drill or bit 23.

Once the machine is brought into operation its action is continuous until it reaches the limit of its forward travel. The forward movement of the power cylinder 11 in the

protecting casing 1 is limited by the annular projection 110 formed round the rear end of the power cylinder 11 engaging the rear end of the bushing 12 in the front end of the casing 1. When the machine reaches the end of its forward movement, the piston 22 then, by driving the impact piece 21 and drill or bit 23 forward, overlaps the port 43 and the actuating fluid escaping by the exhaust port 42 automatically puts the power cylinder 11 out of operation. It is then necessary to retract the machine in the casing 1 and after removing the drill or bit, and inserting a longer tool, the machine is again brought into operation.

In the operation of the machine, in the event of soft material being encountered in which the ordinary bits as employed in percussive tools would so far penetrate the material as to render their rotation impossible and to render the rotative gear inoperative, then the drill or tool could be replaced by one of the auger bit type (see Fig. 17). The shank of such auger bit would be made somewhat shorter than the bits for percussive tools. After the insertion of such a bit, on again starting the machine, the piston 22 would overrun the inlet port 43 for the forward end of the power cylinder 11 and the actuating fluid then escape from the cylinder 11 by the ports 42. When the piston 22 is in this position the percussive apparatus would be put out of operation, while the rotative gear would remain in action and the boring be continued with the auger bit 23^b. Such an arrangement is represented in Fig. 17 of the drawings. In this figure the shank 23^c of the auger bit 23^b is made somewhat shorter than the bit shown in connection with Fig. 2, so that it does not project so far into the bore of the front head 18. This permits the impact piece 21 and piston 22 to assume the positions in which they are shown in Fig. 17, which results in the percussive apparatus being put out of operation while the other parts of the machine are permitted to operate as previously described.

The means for mounting the rock-drilling machine hereinbefore described, and shown in Figs. 1, 9 and 16 of the accompanying drawings, constitute the subject-matter of an application, Serial No. 327469, filed July 24, 1906, for Letters Patent of the United States; and the water-supplying attachments for rock-drilling machines, which are hereinbefore described, and illustrated in Figs. 1, 2, 12 and 15 of the accompanying drawings, constitute the subject-matter of an application, Serial No. 327470, also filed July 24, 1906, for Letters Patent of the United States.

What we claim as our invention and desire to protect by Letters Patent is:—

1. In a drilling or boring machine or engine actuated by fluid pressure, in combination, a casing, a hollow or tubular piece slid-

ingly and non-rotatably carried by said casing, a head or tool holding device revolvably attached to the forward end of said tubular piece inside the casing, a drill or tool operatively carried therein, packing located in the casing between the exterior of said tubular piece and the interior of the casing, means for introducing the actuating fluid to the casing at the rear of said packing to feed the drill, a piston in the tubular piece, means operated by the piston for transmitting to the revoluble piece and drill or bit an intermittent rotary motion in one direction, and means for admitting the fluid to reciprocate 15 said piston.

2. In a drilling or boring machine or engine actuated by fluid pressure, in combination, a casing, a hollow or tubular piece slid- 20 ingly and non-rotatably carried by said cas- ing, a head or tool holding device revolvably attached to the forward end of said tubular piece inside the casing, a drill or tool operatively carried therein, packing between the exterior of said revoluble head and the interior of the casing, means for introducing the actuating fluid to the casing at the rear of said packing to feed the drill, a piston in the tubular piece, means operated by the piston for transmitting to the revoluble piece and 25 drill or bit an intermittent rotation in one direction, a valve located in the tubular piece for alternately admitting the actuating fluid to either end of the piston, and means for introducing the actuating fluid to 30 said tubular piece and valve.

3. In a drilling or boring machine or engine actuated by fluid pressure, in combination, a casing, a hollow or tubular piece slid- 35 ingly and non-rotatably carried by said cas- ing, a head or tool holding device, a drill or tool operatively carried therein, packing be- 40 tween the revoluble head and casing, a cylind- 45 rical piece or ratchet box fixed to the tool holding device, a swivel revolvably attaching said ratchet box to the forward end of the tubular piece, a piston in said tubular piece, means for permitting said piston to recipro- 50 cate therein while preventing it rotating, a rifle nut carried by said piston, a rifle bar working through said rifle nut constructed 55 with a head located in the ratchet box, said head carrying ratchets adapted to be moved in one direction to rotate the ratchet box and tool holding device and free to move in the reverse direction, and a valve and valve box carried by the tubular piece for alternately admitting the actuating fluid to either side of the piston to reciprocate it.

4. In a drilling or boring machine or engine actuated by fluid pressure, in combination, a casing, a hollow or tubular piece of 60 polygonal external section, a cap or cover on the casing shaped internally to correspond to the tubular piece and fitted with a gland 65 through which the tubular piece works, a

revoluble head or tool holding device, a drill or tool operatively carried therein, packing between the revoluble head and casing, means for admitting the actuating fluid to the casing at the rear of said packing, a cylindrical piece or ratchet box fixed to the tool holding device, a swivel revolvably attaching said ratchet box to the forward end of the tubular piece, a cylinder in said tubular piece, a piston in said cylinder constructed 70 with a tail or rearward projection, a nut in which said projection works to prevent the rotation of the piston while permitting of its reciprocation, a valve and valve box carried at the rear of the cylinder inside the tubular 75 piece the cylinder being constructed with ports placing the casing in communication with the valve box and the latter alternately in communication with either end of the cylinder, a rifle nut carried by the piston, a rifle bar working through said rifle nut, said rifle bar being constructed with a head located in the ratchet box, ratchets or pawls carried by said head for locking the rifle bar to the ratchet box and tool holding device 80 when moved in one direction by the piston and rifle nut.

5. In a drilling or boring machine actuated by fluid pressure, the combination of a rotatable power cylinder, a cylinder revolvably 85 connected to the rear end of said power cylinder, means for preventing rotation of said rear cylinder, and means carried by said rear cylinder for rotating the power cylinder.

6. In a drilling or boring machine or engine actuated by fluid pressure, the combination of a rotatable power cylinder, a cylinder 90 revolvably connected to the rear end of said power cylinder, means for preventing rotation of said rear cylinder, and means carried 95 by said rear cylinder for automatically rotating the power cylinder.

7. In a drilling or boring machine or engine actuated by fluid pressure, the combination of a rotatable power cylinder, a cylinder 100 revolvably connected to the rear end of the power cylinder, means for preventing rotation of said rear cylinder, and means located in said rear cylinder and operated by the actuating fluid for transmitting rotary motion to the power cylinder.

8. In a drilling or boring machine or engine actuated by fluid pressure, the combination with a rotatable power cylinder and per- 105 cussive apparatus carried thereby, of an outer shell or casing in which said cylinder is slid- 110 ingly and rotatively mounted, a second cyl- 115 inder rotatively connected to the rear end of the power cylinder, means for preventing rotation of said second cylinder, and means located in said second cylinder for rotating the power cylinder by means of the actuating fluid.

9. In a drilling or boring machine or engine actuated by fluid pressure, the combination 120

with a rotatable power cylinder of percussive apparatus therein, an outer casing in which said cylinder is slidingly and rotatively carried, means for feeding the drill by the pressure of the actuating fluid, a second cylinder rotatively connected to the rear end of the power cylinder, means for preventing rotation of said second cylinder, and means located in said second cylinder actuated by the fluid pressure for rotating said power cylinder.

10. In a rock-drilling or boring machine or engine, the combination of a rotatable power cylinder and percussive apparatus, a drill or tool carried by said power cylinder and means for compelling said drill or tool to rotate with said cylinder, a casing in which the power cylinder is slidingly and rotatively mounted, means for admitting the actuating fluid to the power cylinder to actuate the percussive apparatus, means for utilizing the pressure of the actuating fluid to feed the drill, a second cylinder rotatively connected to the rear end of the power cylinder, means for preventing rotation of said second cylinder, and means located in said second cylinder for rotating the power cylinder by the pressure of the actuating fluid.

11. In a drilling or boring machine or engine actuated by fluid pressure, the combination of a rotatable power cylinder and percussive apparatus therein, an outer casing in which said power cylinder is slidingly and rotatively carried, means carried by said cylinder for admitting the actuating fluid to said power cylinder to actuate the percussive apparatus, a second cylinder rotatively connected to the rear end of the power cylinder, means for preventing rotation of said cylinder, means located in said cylinder adapted to be actuated by fluid pressure for rotating the power cylinder, and means for admitting alternately to either end of said rear cylinder the actuating fluid to actuate the mechanism for rotating the power cylinder.

12. In a drilling or boring machine or engine, the combination of a rotatable power cylinder and percussive apparatus therein, an outer casing, means carried by the power cylinder for admitting the actuating fluid to said cylinder to actuate the percussive apparatus, means for supporting the drill bit or tool at the forward end of said power cylinder, said means compelling the bit or tool to rotate with the cylinder, means for utilizing the pressure of the actuating fluid to feed the drill, a second cylinder rotatively connected to the power cylinder at the rear end, means for preventing rotation of said second cylinder, means interposed between the power cylinder and rear cylinder for imparting rotary motion to the power cylinder, means located in the rear cylinder for actuating said rotative gear, and means carried by the rear cylinder for controlling the admission of the

actuating fluid to said cylinder to operate said rotating gear.

13. In a drilling or boring machine or engine, the combination of a rotatable power cylinder and percussive apparatus therein, an outer casing in which said power cylinder is slidingly and revolvably supported, means for admitting the actuating fluid to the rear end of said casing, means carried by the power cylinder for admitting the actuating fluid to said cylinder to actuate the percussive apparatus, means located at the rear of the power cylinder which by confining the motive fluid at the rear end of said cylinder utilizes the pressure of said fluid to feed the drill, a tail pipe revolvably attached to the rear end of the power cylinder, means carried by the casing for preventing the rotation of said tail pipe, a cylinder located in said tail pipe at the rear of the power cylinder, rotating mechanism interposed between the two cylinders, means in the rear cylinder for actuating said rotating mechanism, and means carried by the rear cylinder for admitting the actuating fluid alternately to either end of said cylinder to operate the rotative mechanism.

14. In a drilling or boring machine or engine, the combination of a rotatable power cylinder and percussive apparatus therein, a protective casing in which said cylinder is slidingly and rotatively carried, a tubular tail piece revolvably connected to the power cylinder, inside said casing, ratchet mechanism located between said tail piece and power cylinder adapted to impart an intermittent rotary motion to the latter, a cylinder supported in the tail piece, a piston arranged in said cylinder carrying a nut for engaging a rifle bar actuating the ratchet mechanism, means for admitting alternately to either end of said piston a quantity of the actuating fluid to actuate the ratchet mechanism to rotate the power cylinder about its point of attachment to the tail piece, and connections for preventing the rotation of the tail piece, cylinder and piston.

15. In a drilling or boring machine or engine, the combination of a rotatable power cylinder and a reciprocating percussive member therein, means for slidably and non-rotatably supporting a drill or bit in the forward end of said cylinder in position to receive the impacts of said percussive member, an outer protective casing inclosing said power cylinder and permitting rotation of the latter, a valve and valve box carried by the power cylinder for controlling the admission of the fluid thereinto to actuate the percussive member, a valve box cap secured to the rear end of the power cylinder, packing located between the valve box cap and the inside of the casing which packing forms said valve box cap into a piston to feed the drill by the fluid pressure, a cylinder revolvably

attached to the rear end of the power cylinder and carried by the casing, means for preventing rotation of said rear cylinder, and means located in said rear cylinder for imparting intermittent rotation to the power cylinder and drill or bit, substantially as described.

16. In a drilling or boring machine or engine, the combination of a casing and a power cylinder rotatively and slidably mounted therein, a reciprocating percussive member in said power cylinder, means for slidably and non-rotatably supporting a drill or bit in the forward end of the power cylinder in position to receive the impacts of the percussive member, a valve and valve box carried at the rear end of the power cylinder for admitting the actuating fluid alternately to either end of the power cylinder, a valve box cap secured to the rear end of the power cylinder, packing located between said cap and the interior of the casing, a port in said cap placing the valve box in communication with the casing at the rear of the packing for admitting the actuating fluid to the rear of said valve box cap, a tail pipe or extension of polygonal external section revolvably attached to the valve box cap, a cap fitted at the rear of the protecting casing through which the tail pipe works, packing between said cap and tail pipe, a piston in said extension, a valve carried by said extension for controlling the admission of the actuating fluid to either end of said piston, and means actuated by the piston for imparting an intermittent rotary motion to the power cylinder and bit, substantially as described.

17. In a drilling or boring machine or engine, a rotatable power cylinder, containing percussive apparatus, a drill or tool carried by said power cylinder and means for compelling said drill or tool to rotate with said cylinder, a second cylinder rotatably connected to the rear end of said power cylinder, means for preventing rotation of the second cylinder, means carried by said second cylinder for rotating the power cylinder, and a valve and connections for retaining the rotation means in action when the percussive apparatus is put out of operation.

18. In a drilling or boring machine or engine, a casing having a bushing secured to the forward end of the casing and provided with holes or ports, a power cylinder slidably and rotatably fitting said bushing, means for rotating said power cylinder, and a tail piece rotatably engaged with the power cylinder and held by the casing against rotation.

19. In a drilling or boring machine or en-

gine, a casing having a rear cap, a power cylinder rotatively and slidably mounted in said casing and non-rotatably carrying a drill or bit at its forward end, a tail piece or pipe slidably and non-rotatably fitting said rear cap and revolvably attached to the power cylinder within the casing, packing surrounding the rear end of the power cylinder and arranged between said cylinder and the interior of the casing, and means for supplying fluid under pressure to the casing at the rear of said packing, in combination with means for imparting intermittent rotation to the power cylinder and including a piston mounted for reciprocation in the tail piece or pipe and held against rotation therein, a rifle nut carried by the piston, a rifle bar engaged by said nut, and a pawl and ratchet mechanism connecting said rifle bar with the rear end of the power cylinder.

20. In a drilling or boring machine or engine, a casing, a power cylinder rotatively and slidably mounted in said casing and non-rotatably carrying a drill or bit at its forward end, a tail piece or pipe slidably and non-rotatably fitting the casing and revolvably attached to the power cylinder within the casing, and means for supplying fluid under pressure to the casing, in combination with means for imparting intermittent rotation to the power cylinder and including a piston within the tail piece or pipe, means for controlling admission of the actuating fluid to either side of said piston and rotative mechanism engaging the piston and the power cylinder.

21. In a drilling or boring machine or engine, a casing, a power cylinder rotatively and slidably mounted in said casing and non-rotatably carrying a drill or bit at its forward end, a tail piece or pipe slidably and non-rotatably fitting the casing, and means for supplying fluid under pressure to the casing, in combination with means for imparting intermittent rotation to the power cylinder and including a piston within the tail piece or pipe, means for controlling admission of the actuating fluid to either side of said piston and rotative mechanism engaging the piston and the power cylinder.

In witness whereof we have hereunto set our hands in the presence of two subscribing witnesses.

HENRY HELLMAN.
